UNITED STATES PATENT OFFICE.

CHARLES M. FITCH AND FOREST G. MOORE, OF KANKAKEE, ILLINOIS, ASSIGNEES TO SEARS, ROEBUCK AND CO., OF CHICAGO, ILLINOIS, A CORPORATION OF NEW YORK.

PORTABLE OIL HEATER.

Application filed July 15, 1926. Serial No. 122,532.

The invention pertains to improvements in portable oil heaters of the type which embodies a base and a drum hinged thereon, and has especial reference to the provision 5 in such a heater of a device for releasably locking the base and drum together. In this particular type of heater, precaution must be taken against upsetting the heater. For this reason an especially efficient and pos- 10 tively operating latch is necessary to guard against accidental unlatching and consequent tipping of the base when the heater is being carried from place to place.

It is an object of this invention to provide 15 a novel latch for an oil-heater which is so constructed that the possibility of accidental operation of the latch is reduced to a minimum.

Another object is to produce a latch which 20 is highly efficient in operation, positive in action and may be simply and cheaply manufactured.

Other objects and advantages will become apparent from the following description and 25 the accompanying drawings in which:

Figure 1 is an elevation of the lower portion of an oil-heater.

Fig. 2 is an enlarged vertical section taken on the line 2-2 of Fig. 1.

30 Fig. 3 is an enlarged fragmentary vertical section taken on the line 3-3 of Fig. 2 and showing the pivot-pin and spring of the latch.

While we will herein illustrate and de- 35 scribe our invention with considerable particu-larity it is contemplated that various changes in the construction and arrangement employed may be made by those skilled in the art without departing from the scope 40 of the invention as expressed in the appended claims.

In the particular type of oil-heater for 45 which our latch is especially adapted, a radiating drum 5 forming the upper part of the heater has secured at its lower end, a skirt 6, which is arranged to project downwardly over the upper rim of a base 7 of the heater and which is hingedly connected thereto as by means of a suitable hinge 8.

50 The latch mechanism is located at a point substantially opposite the hinge.

In the preferred form, the latch comprises an arcuate member 9 bent at the lower end to form a hook 10, and a keeper 11 secured 55 to the inside of the base 7 and adapted to be

engaged by said hook. As a means for strengthening the hook member 9 the edges are turned inwardly to provide side flanges 12. Near the upper end of the hook member, the flanges 12 are enlarged, to form 60 two parallel spaced ears 13. The upper end of the hook member 9 extends through an opening 14 formed in the skirt 6 and constitutes a trip 15 for disengaging the hook 9 from the keeper 11. Opposite side edges 65 of the opening 14 are turned inwardly to provide lugs 16 which overlap the ears 13. The hook member 9 is suitably pivoted on a pin 17 extending through the lugs 16 and 70 the ears 13.

As may be seen in Fig. 2, the position of the hook member 9 when mounted on the skirt 6 is such that the portion which extends inwardly is located within the base 7 when the drum 5 is in its normal position. 75 When the drum 5 is moved into closed position, the hook 10 will engage the keeper 11 to hold the drum in position.

This, in effect, is a gravity actuated latch, 80 automatically operating upon swinging the drum to close the heater. It has been found, however, that it is possible to tip a heater having this type of latch, to certain positions at which the latch will swing away from the keeper to disengage itself therefrom. In order to insure that the hook 10 will positively engage the keeper 11 in all 85 positions of the heater a coil spring 18 is positioned on the pin 17. One end of the spring extends through a hole 19 in the hook member 9 to bear against the inner surface of the skirt 6, and the other end bears against the inner surface of the trip 15. One edge of the hole 19 is preferably struck outwardly to provide a finger or stop 20 overlying the skirt 6 and adapted to limit the downward movement of the hook member 9. To release 90 the latch, the trip 15 is depressed to move the hook member from the full line position to the broken line position as shown in 95 Fig. 2.

It will be readily apparent that a latch has been provided in which only a small part extends outwardly from the heater. This minimizes the possibility of the latch being accidentally operated to cause the heater to be upset. The latch is located in a very convenient place for operation, it being readily operable by either hand or foot.

Furthermore, the relative position of the 110

trip 15 and the skirt 6 renders it possible to grip the parts between the thumb and forefinger, thus depressing the trip so as to disengage the latch as the skirt of the drum is 5 grasped for the purpose of tilting it on the base.

We claim as our invention:

1. In an oil-heater, in combination with a base and a drum hingedly attached to the 10 base and having a peripheral skirt encircling the upper end of the base, a latch comprising a keeper rigidly secured within said base, said skirt having a slot therein, and a member pivotally mounted on said skirt and extending through said slot with one end projecting inwardly and downward into the 15 base and normally adapted to engage said keeper, and with its other end projecting upwardly and outwardly so as to be disposed above the skirt in spaced relation thereto.
2. In an oil-heater, in combination with a lower part and an upper part hingedly connected thereto, a latch comprising a keeper rigid with said lower part, an arcuate 25 hook member hinged to said upper part in such position that one end thereof is normally adapted to engage said keeper, and the other end thereof extends outwardly from said upper part to provide a means to dis- 30 engage said first mentioned end from said keeper, spring means arranged to force said hook member into positive engagement with said keeper, and means whereby the motion of said hook member is limited.
3. In an oil-heater, in combination with a lower part and an upper part hingedly at- 35

tached thereto, a latch comprising a keeper rigidly secured within said lower part, and a hook member within said lower part, said member being pivotally mounted on said upper part for movement into and out of engagement with said keeper, and having a part extending externally of said heater to constitute a trip for disengaging said hook member and said keeper.

4. In an oil-heater, in combination with a lower part and an upper part hingedly connected thereto, a latch comprising a keeper rigidly secured within said lower part and a hook member within said lower part, said member being pivotally mounted on the upper part in such position as to be swung by gravity into engagement with said keeper during the closing of the heater, and means acting on said latch to resist the disengagement of said hook member from said keeper.

5. In an oil-heater, in combination with a lower part and an upper part hingedly attached thereto, a latch comprising a keeper rigid with said lower part, a hook-member 60 pivotally mounted on said upper part in such position as to be swung by gravity into engagement with said keeper during the closing of said upper part onto said lower, and resilient means acting to resist the disengagement of said hook member from said keeper.

In testimony whereof we have hereunto affixed our signatures.

FOREST G. MOOR.
CHARLES M. FITCH.
